UNITED STATES PATENT OFFICE.

JULIUS S. FOX, OF CLEVELAND, OHIO.

LAUNCHING AND LANDING STATION.

Application filed September 27, 1926. Serial No. 137,892.

This invention relates to launching and landing stations and particularly to stations for aerial vehicles which should have suitable stations from which to start on a proposed trip and at which they may land, and where certain load such as mail and express may be conveniently deposited, and passengers may safely land at their destination or board when starting from such end 10 of a route.

To provide the arrangement of structures for accomplishing the stated results, it is my purpose to construct a launching and landing platform adjacent a building which latter is provided with a roofed central portion to receive the vehicle, such as an aeroplane, and which may be of the hydroplane type, and erect the platform that shall be capable of swinging in a vertical plane to bring one end thereof in close proximity to the building and at different heights relative to it, while the opposite end of the platform may be raised or lower above or below the level of the particular floor of the building with which it is designed to be placed on a common level when vehicles are to be moved from one support to the other.

It is an object of my invention to provide a building having a plurality of floors superposed and one of the intermediate floors having a broad corridor extending the length of the building, one end of which communicates with the street and the other with a transverse opening readily reached from the swinging platform, thus providing suitable relative positions of the stationary building and the movable launching and landing platform.

It is a further object of my invention to provide a launching and landing station comprising a stationary building having a plurality of floors, one of which serves as a basement for entrance of employees and other persons to remove and classify package articles dropped from the upper floor at which the aerial vehicles have arrived, an intermediate floor for landing thereon, and an upper floor for offices or other purposes for transportation and communication; and a platform adjacent the intermediate floor of the building and movable in a plurality of planes to swing the platform vertically, and also upon a vertical axis, to bring the platform into different positions relative to the landing floor of the building.

Driving means is provided to move the platform as required which may use different forms of power, though shown as using electric power for the purpose.

With these and other objects in view, I have shown the structure and principle of operation of my invention by the description hereinafter included, the claims appended, and the drawings in which the invention is illustrated, and in which—

Figure 1 is a plan view of the launching and landing station;

Figure 2 is a side elevation of the same;

Figure 3 is a side elevation of the swinging platform and base, portions being broken off;

Figure 4 is a side elevation of one end of the platform;

Figure 5 is a side elevation of the base for the platform, together with the actuating means for the platform;

Figure 6 is a side elevation of the base for the platform, and on a larger scale, bearings being shown in section;

Figure 7 is a plan view of the structure appearing in Fig. 5;

Figure 8 is a detail view of the actuating sector gear and its securing means for attachment to the platform, and

Figure 9 is a rear view of the building, showing the landing floor thereof, and the traveling crane mounted within the corridor above the vehicles.

The landing station comprises the main stationary building 5 having a front entrance stairway 6 and a rear, open, launching and landing space 7 on the intermediate floor 8 which is normally adjacent the extended pier 9, at the outer end 10 of which is supported a scaffolding 11, upon which is supported the upright base 12 having a flat top piece 13 upon which rests an inverted dish-shaped bearing part 14 by which is rotatably mounted the movable platform 15, the details of which will be described later.

Upon the bearing part or cap 14, are secured in spaced and parallel relation, approximately triangular plates 16 having outwardly-bent flanges 17 at their base edges, these flanges 17 being secured to the flat portion of the part 14 by means of bolts or other locking mechanism 18. The apexes of the plates 16 are curved at their edges 19, and are provided with bearing apertures 20 to 110

receive therein an axis of a swinging structure bearing directly thereon the platform 15.

The main, or what might accurately be termed the intermediate floor 8 of the building 5, has broad corridors or open space 7 extending the length of such building, the rear end of such space being shown especially in Fig. 9 of the drawings. The side 10 walls 21 of such space 7 extend the full length of the space, but lack a portion of the height of this main floor, thus providing upper ledges 22 for tracks upon which travel cranes 23 one of which is shown in Fig. 9. 15 This overhead crane travels toward and from the pier 9, and serves to load or unload an aerial vehicle or even raise or lower the vehicle itself.

At either side of the main corridor 7 of 20 the floor 8, are narrow hallways 24 in which are provided stairways leading down to the basement 25 or up to the upper floors, and if desired, provided with the usual elevators for passengers or baggage. The relative 25 arrangement of the building and the platform 15 I regard as important and is the result of special consideration of the advantages to be derived from their relation in forming a suitable station for aerial vehicles 30 to land safely and discharge their load, or to conveniently plan their launching from the building out upon the platform 15 and finally travel in the usual manner of aerial ascent. The particular arrangement of the 35 stationary building and the base support of the platform 15 enables the use of any desirable starting mechanism on the main floor 8 at the rear space 7, for the purpose of attaining desired speed of the propeller before 40 attempting flight, and even before traveling out on the platform 15 preparatory to aerial flight. Also, any desirable barrier mechanism for use on the platform or building space 7 may readily be utilized for halting the vehicles in a short distance when 45 landing.

Parts 11 to 20 are constructed in a manner to properly drive the platform 15 in a direction and in relation to the floor 8, as will 50 now be explained. The scaffolding or low tower 12, supports thereon the platform 15 through the means of certain driving agencies by which the platform may be rotated upon a vertical axis, and also oscillated 55 upon a horizontal axis, the former adjustment designed to swing the platform 15 to bring the rear end thereof 25 adjacent different portions of the main floor of the building 5, and the latter movement being 60 designed to raise or lower either end of the platform 15 for purposes of launching or landing purposes.

The driving means for moving the platform on a vertical axis comprises an annular 65 gear 26 having the edge driving teeth 27

with which engage the pinion 28, itself driven by an endless chain 29, mounted on the sprocket 30 fixed to a convenient frame part of the tower 12 and an opposite sprocket 31 mounted on a short shaft of an electric 70 motor 32 supported upon a floor piece 33 secured to the frame of the tower beneath the part 14. To provide proper mounting of the platform in this manner, the upper plate 13 has a central circular aperture 34 of 75 sufficient size to receive therein the gear 26 with sufficient peripheral space about it. At the center of the bearing part 14 and upon the upper or outer surface thereof, is provided a hub part 35 within which is an axial and polygonal opening through which is passed and secured therein a correspondingly-shaped shaft 36 which is designed to extend down through the aperture 34 and secured against relative rotation to the gear 26, as by a spoke construction in the gear 26.

By such described mounting of parts, the driving of the gear 26 will rotate the part 14 and any structure carried thereby, as will be evident. To reduce friction between such rotating parts to a minimum, an annular flange 37 is provided upon the plate 13 and about the aperture 34, and having an upper annular raceway 38 thereon and an outer vertical surface 39 which guides the annular flange 40 of the cap 14. The interior or under surface of the cap 14, spaced from the flange 40 has an annular ball race 41 which is brought into complementary relation with 38, when the flanges 37 and 40 are telescoped, as illustrated in Fig. 6 of the drawings. The usual bearing balls 42 are guided in the said races.

The platform 15 may be constructed for the movements mentioned for adjustment, 105 by spacing parallel side members 43 thereof by means of any suitable cross members, not shown in detail, because not especially concerned in this invention. The members or walls 43 may support therebetween a 110 tread surface 44, of which a portion 45 may be provided with a relatively movable element 46 beneath which rotatably-mounted members 47 may be used to support the upper run of said moving element 46. Upon 115 the outer surfaces of the walls 43, and adjacent the lower edges of the latter intermediate the ends of the platform, are secured heavy plates 48 having a gear sector portion extending downward therefrom and integral therewith, the upper portion thereof having any desired form and having a convenient number of perforations therethrough to receive bolts or rods extending through the 120 perforations of both plates 48 as well as through the members 43, so that the plates bearing the gear sectors thereon will be rigidly attached to the platform, whereby driving the gear sectors will oscillate the 125 platform.

In the approximate center of the plates 48 are bored relatively large apertures 49 which, when the platform is mounted upon the tower in movable position, will be brought into alinement with the apertures 20 in the plates 16, after which an axial pin 50 is positioned through the apertures 20 and 49, which pin receives the weight of the platform 15 thereon and permits the oscillation of the same on said horizontal pin 50. Mounted on the plate 14 are spaced motors 53 having on their shafts 51, pinions 52 which engage the sectors of the plates 48 for driving the latter, the two plates, respectively. The rocking of the plates 48, therefore, upon the pin 50, together with the attached platform 15, oscillates the latter. Upon the plate 14, therefore, is mounted the entire structure of the platform and its support and driving mechanism, and whose detailed character does not especially concern the invention herein claimed. The only essential structure I contemplate, is the mounting of the driving motors 53 upon the rotatable plate 14 for rocking the parallel walls 43, and the mounting of the motor 32 upon the tower 12 for driving the cap member 14 with its entire load carried thereon.

Many details of the construction have more or less bearing upon the intended function of the entire mechanism, but though shown and described in this application, are considered conventional in their importance per se, but are important in their use combined with the structures here brought together in a new and useful arrangement for accomplishing new functions. At the ends of the platform 15, are provided landing extremities 55 comprising thin and wedge-shaped plates whose lower surfaces are inclined upwardly toward the ends thereof. Also, the upper edges of the side walls 43 of the platform are extended upwardly at 56 throughout the greater portion of the intermediate distance between the inclined ends 55, above the tread to serve as a guide rail or safety ledge. It is also to be noted that the central dotted-line partition of the space below the corridor on the main floor 8, is designed to apply only to the partitioning of such space in the basement 25. The third or higher floors above the main floor 8 may be used for offices for any desired purposes, and is shown only diagrammatically in these drawings.

It is to be understood that my invention is by no means intended to be limited to the use of such combined station building 5 and platform 15 adjacent thereto, upon any particular ground foundation therefor, though it will often be found advisable to construct the building 5 with a main floor 8 fully one story above the level of the ground. This provides opportunity for lowering the outer end of the platform 15 to at least the cor-

responding distance. As illustrated in Fig. 2, the platform 15 is shown as having a tower 12 substantially on a level with the floor 8, and the said view is readily adaptable to use where the pier 9 and such tower 12 is built over and above a water surface as 60. But this particular use for hydroplanes is only suggestive, and need not be made use of in gaining the advantages of the invention, for the pier and related parts 75 may overhang dry ground or an artificial floor of conventional character as well.

Having thus described my invention what I claim as new and desire to secure by Letters Patent of the United States is as follows—

1. A launching and landing station comprising a building having on one floor a broad corridor opening directly outwardly, an elongated platform pivoted in a plurality of planes, upon a support spaced from said opening to bring one end of the platform closely adjacent the corridor floor in one of its positions, and a traveling crane mounted upon ledges of the side walls adjacent the ceiling of said floor, for travel toward and from the outer opening.

2. A launching and landing station comprising a building and a movable platform having a supporting base continuous with and extending outward from said building, the main floor of the building having an outer opening facing the platform and an oppositely-positioned entrance means, an upright frame mounted on the extreme end of said base, and power-driven mechanism on said frame for actuating said platform for movement in at least one plane, the fulcrum of said movement being directly over said upright frame.

3. A launching and landing station comprising a building and an elongated movable platform spaced therefrom, the platform having a supporting pier which is continuous with and extends outward from said building, an upright supporting base mounted upon the end of the pier farthest from the building, power-driven mechanism on said base supporting said platform for swinging the platform on said base in a vertical plane, and actuating the platform in said swinging movement, so that when in a horizontal position, one end of the platform will be closely adjacent the main floor of the building, said main floor having an open space opening outwardly and facing said platform, whereby an aerial vehicle may readily launch from said space in the building outwardly upon the platform and then from the latter in aerial flight.

4. In an aerial station, a building having at least three, superposed stories, the main or second story having a broad, open floor space opening outwardly in a direction opposite from the street upon which the build-

ing faces, and having side hallways, partitioned from said broad space, and leading to the floors above and below said main floor, a basement floor having entrance openings laterally to the main ground surface, the said main floor being equipped with traveling cranes for loading and unloading aerial vehicles on said main floor, in combination with a swinging platform mounted rearwardly from said building and so spaced

from the latter that it may be moved upon its foundation to bring one end thereof into close proximity to said main floor of the building, and power-driven mechanism upon said foundation for actuating said 15 platform in its swinging movement.

In witness whereof I have hereunto set my hand and seal this 21st day of September, 1926.

JULIUS S. FOX.
